UNITED STATES PATENT OFFICE

148,155

DESIGN FOR A BOX

Frederic H. Fisher, Syracuse, N. Y., assignor to Syracuse Ornamental Co. Inc., Syracuse, N. Y., a corporation of New York

Application May 10, 1946, Serial No. 129,521

Term of patent 3½ years

(Cl. D58—12)

To all whom it may concern:

Be it known that I, Frederic H. Fisher, a citizen of the United States, residing in Syracuse, in the county of Onondaga and State of New York, have invented a new, original, and ornamental Design for a Box, of which the following is a specification, reference being had to the accompanying drawing, forming a part thereof.

Fig. 1 is a top view of a box showing my new design; and

Fig. 2 is a side perspective view with the cover partially removed.

The sides of the box which are not disclosed are substantially like the corresponding sides shown.

I claim:

The ornamental design for a box, substantially as shown and described.

FREDERIC H. FISHER.
